UNITED STATES PATENT OFFICE

170,052

ROCKING HORSE

Isabel Goss, Lawndale, Calif.

Application October 1, 1951, Serial No. 16,799

Term of patent 14 years

(Cl. D34—15)

To all whom it may concern:

Be it known that I, Isabel Goss, a citizen of the United States, residing at Lawndale, California, have invented a new, original, and ornamental Design for a Rocking Horse, of which the following is a specification, reference being had to the accompanying drawing forming a part hereof.

Fig. 1 is a front perspective view of a rocking horse, showing my new design; and

Fig. 2 is a rear perspective view thereof.

The side of the rocking horse not shown has substantially the same appearance as the side shown in Fig. 1.

The drawing figures are lined to indicate color contrast.

I claim:

The ornamental design for a rocking horse, as shown and described.

ISABEL GOSS.
